(57) **CLAIM**

The ornamental design for a toolbox interior, as shown and described.

DESCRIPTION

FIG. 1 is a top right perspective view of a toolbox interior of the present invention;

FIG. 2 is a top left perspective view thereof; and,

FIG. 3 is a front elevation view thereof.

Rear, left and right elevation views, as well as top and bottom plan views, have been omitted as they do not form a portion of the claimed design and the claimed design is clearly understood and fully disclosed in the perspective and front views. The evenly spaced broken lines showing a tool box and portions of the insert are for the purposes of illustrating environment, and form no part of the claimed design.

The long and short broken lines are boundary lines which define the bounds of the claimed design. These boundaries do not exist in reality in the article embodying the design. It is understood that the claimed design extends to these boundaries but do not include the boundaries.

1 Claim, 3 Drawing Sheets

FIG. 1.

FIG. 2.

FIG. 3.
